UNITED STATES PATENT OFFICE.

OWEN E. GRIGSBY, OF PARK RIDGE, ILLINOIS, ASSIGNOR TO PORCELAIN TILE COMPANY, OF CHICAGO, ILLINOIS, A CORPORATION OF ILLINOIS.

TILED CONSTRUCTION.

Application filed April 18, 1928. Serial No. 270,941.

Patent No. 1,594,614, granted August 3, 1926, to George D. Haines, discloses a tiled wall construction comprising a base or foundation sheet secured to any suitable supporting structure, said foundation sheet having grooves to receive the marginal flanges of enameled sheet-metal tiles. The grooves serve to locate the tiles in horizontal alinement and to insure proper staggering of joints.

The object of the present invention is to extend the use of the self-aligning and locating feature to molded tile, as, for example, tiles made of glass, clay, and other materials which are too fragile to permit of the formation of thin marginal flanges.

In the accompanying drawings,

Figure 1 is a fragmentary face view of a wall embodying the features of my invention, a portion of a wall extending at right angles to the first-mentioned wall being shown in cross-section.

Fig. 2 is a fragmentary view upon an enlarged scale, showing the base sheet in section and two tiles in edge elevation.

Fig. 3 is a rear side view of a molded tile embodying the invention.

Fig. 4 is an edge view of the tile shown in Fig. 3.

Fig. 5 is a rear view of a half-length tile embodying the invention.

The invention is adapted for use in connection with interior or exterior walls, floors, wainscoting, fireplaces, tiled surfaces enclosing built-in bath tubs, store counters and the like. The supporting structure to which the tiled surface is to be applied may be of any preferred construction, that herein shown consisting of a plurality of vertical wooden studs 1 constituting the ordinary framework of a wall or partition. To the studs is nailed or otherwise secured a rigid base sheet 2 of mineral or fibrous material. In the face of the sheet 2 are two sets of parallel equidistant grooves, one set being at right angles to the other so that the grooves intersect to form squares. The sheet 2 is relatively large so as to afford support for a large number of tiles.

Referring now to Figs. 3 and 4: A is a tile molded of glass, clay or other suitable plastic material, said tile having upon its rear side ribs extending perpendicularly to each other and adapted for insertion into the grooves 3 of the base sheet at the places where said

grooves intersect each other. In the construction shown in Figs. 3 and 4, the tile is provided with a longitudinal rib A¹ located centrally upon the back of the tile, there being two ribs A² extending perpendicularly to the rib A¹ and spaced apart a distance equal to the distance between two adjacent parallel grooves in the base sheet.

In order that a narrow space shall be left between the tiles to allow for irregularities and to receive a thin filling of cement, the width of the tile A is made slightly less than the distance between the centers of two adjacent grooves 3, and its length is approximately twice its width.

In practice, the tiles may be 3" x 6", 4 1/4" x 8 1/2", or any other standard size employed in tiled constructions.

In order to complete courses, half-length tiles A³ may be provided, as indicated in Figs. 1 and 5. Such square or half-length tiles are provided upon their rear sides with a centrally located vertical rib A⁴ and a centrally located horizontal rib A⁵, said ribs being adapted to be set in an intersection of the grooves 3.

In tiling the walls of a room, for example, in accordance with this invention, large sheets 2 are secured to the studs, furring or other supports. Tiles are then cemented in place, the tiles being coated on their edges, backs and flanges with cement and set against the base sheet, the flanges being placed in the grooves 3. In Fig. 2, the film of cement between the tiles and the base sheet and between adjacent tiles is indicated at x. The grooves 3 serve to locate the tiles in proper horizontal alinement, and also space the tiles so that they break joints regularly; hence the setting of the tiles may be done rapidly and without the necessity of exercising skill and care.

It will be apparent that the ribs on the backs of the tiles may be made as wide as necessary in order to obtain sufficient strength, and that the grooves 3 may be made as wide as necessary to receive the ribs on the tiles.

I claim as my invention:

1. Tiled construction comprising a supporting structure, a base sheet secured to said structure, said sheet having in its face two sets of parallel grooves, one set intersecting the other, and molded tiles cemented to said base sheet, each of said tiles having

a rib arranged centrally upon its back, and another rib intersecting the first mentioned rib, said ribs lying in the intersecting portions of said grooves.

5 2. Tiled construction comprising a supporting structure, a base secured to said structure, said base consisting of a plurality of relatively large rigid sheets, each sheet having in its face parallel recesses, and a mul-

tiplicity of molded tiles, cemented to each 10 of said base sheets, each of said tiles having upon its back centrally disposed projections lying in said recesses, said recesses and projections serving to locate and aline the tiles horizontally and vertically.

15 In testimony whereof, I have hereunto affixed my signature.

OWEN E. GRIGSBY.
